United States Patent Office.

DAVID YOUNG, OF EAST TOPSHAM, VERMONT.

Letters Patent No. 77,342, dated April 28, 1868.

IMPROVEMENT IN SUGAR-PAN DERRICK.

The Schedule referred to in these Letters Patent and making part of the same.

TO ALL WHOM IT MAY CONCERN:

Be it known that I, DAVID YOUNG, of East Topsham, in the county of Orange, and State of Vermont, have invented a new and improved Sugar-Pan Derrick; and I do hereby declare that the following is a full, clear, and exact description thereof, which will enable those skilled in the art to make and use the same, reference being had to the accompanying drawings, forming part of this specification, in which—

Figure 1 is a side view of my improved derrick, with a removed section, showing the tongue.

Figure 2 is a horizontal section of the same, through the line $z z$, fig. 1.

Similar letters of reference indicate corresponding parts.

This invention relates to the moving of sugar-pans from the arches on which the same are placed for evaporating the sap or cane-juice.

It consists of a derrick formed of an upright, A, and two horizontal beams, B, braced with brackets, D, in the usual manner, in combination with the other devices perfecting the whole, for the purpose required, which will hereinafter be more fully set forth.

The block E is made with its two lower corners or edges recessed, to form a tongue, as shown, which fits between the beams B B, so that the said block may rest securely thereon without being affixed thereto.

Through a mortise in the block E the vertical staff G fits with easy contact, and is movable up or down. To the lower end of the said staff is affixed a frame, shaped like the letter H, it being simply a cross-piece, a; (the length of which is or approximates to the width of the common sugar-pans,) and parallel pieces, b b, (the length is or approximates to the length of common sugar-pans,) mortised or otherwise affixed firmly together, as shown.

At each end of the pieces b, two hooked rods or links, d, are loosely attached for the purpose of hooking into corresponding loops, rings, or links, c, at the corners of the sugar-pans M, as they rest upon the arch or arches N.

A cord, rope, or chain, I, passes from the windlass h over the pulley J in the beams B, and the pulley e in the block E, and thence down through a hole or channel in the block to the frame at the bottom of the staff, where it is affixed to the said frame by a shackle-rod and pin, as shown, or in any other suitable manner. By this device the pans may be raised from the arches, and swung away from the same in the manner common to derricks.

The block E slides along on the beams B when made to do so by pushing or pulling the staff G, whereby the frame and hooks can thus be brought over each of the several pans on the arches successively, but when not so pushed or pulled, the friction of the block upon the beams is generally sufficient to hold it against tendency to move along on the beams, which may be occasioned by the cord I, but if not, holes may be made laterally through the beams B, and a similar hole in the block E, for the reception of a key or pin to hold the block securely.

By the crank-handle L the cord is wound or unwound on the windlass h, and the pan M raised or lowered at will.

The upright, A, swings on the post F, by eye-and-pintle hinges, as shown, and a rod or peg, P, passes through a hole in the upright, A, and also in the post F, to hold the derrick in a fixed position over the sugar-pans in the arches. This peg is withdrawn when the pans are to be swung off after being lifted clear of the arches.

Iron pins i, radiating from the windlass h, serve, in connection with a removable pin, j, to hold the windlass from unwinding and lowering the pan at any point of its suspension. The pin j may be attached by a cord to the upright A, or other convenient point.

The staff G steadies the pans when lifted and swung off, so that the syrup may not be spilled. The block E enables the staff and frame to be brought over the different pans on the arches.

My improved derrick can be cheaply constructed of wood, and supplies a want long felt in the manufacture of maple and sorghum-sugar, where the pans heretofore were lifted from the arches by hand.

I claim as new, and desire to secure by Letters Patent—

1. The steadyng-staff G and frame $a\ b\ b$, substantially as shown and described, in combination with the cord I and derrick A B D, all as and for the purpose set forth.
2. The block E, bearing the pulley e, and held between the arms B of the derrick, when said block is slotted for the passage of the vertical bar G, which steadies the pan as it is elevated by the cord I, as herein shown and described.
3. The arrangement of the steadyng-bar G, frame $a\ b\ b$; pulley e, slotted block E, arms B, and elevating-cord I, with relation to the derrick A D, whereby a series of pans in a row is elevated in a vertical line without removing the derrick, as herein shown and described.
